CLAIM

The ornamental design for a personal security alarm, as shown and described.

DESCRIPTION

FIG. 1 is a front, top perspective view of a personal security alarm, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and

FIG. 8 is a bottom plan view thereof; and,

FIG. 9 is an enlarged view of the area labeled 9 in FIG. 1. The broken lines show portions of the personal security alarm that form no part of the claimed design.

The dot-dash broken lines of the personal security alarm in FIG. 1 illustrate a boundary and cut line of the enlarged view in FIG. 9 and form no part of the claimed design.
